J. E. BURNS.

DENTAL CASTING MACHINE.

APPLICATION FILED NOV. 24, 1917.

Patented July 16, 1918.

INVENTOR,

John E. Burns,

BY

James F. Duhamel,

ATTORNEY

UNITED STATES PATENT OFFICE.

JOHN E. BURNS, OF FLUSHING, NEW YORK.

DENTAL CASTING-MACHINE.

1,272,912.

Specification of Letters Patent. Patented July 16, 1918.

Application filed November 24, 1917. Serial No. 203,635.

To all whom it may concern:

Be it known that I, JOHN E. BURNS, a citizen of the United States, and resident of Flushing, in the county of Queens and State 5 of New York, have invented certain new and useful Improvements in Dental Casting-Machines, of which the following is a specification.

This invention relates to dental casting machines and more especially to means for closing the molding flask with a cap through which compressed air is then admitted to the flask and upon the molten metal, the object of the invention being to 10 automatically admit the air as the cap closes the flask and by the continued movement of the operating lever, as will be more fully described in the following specification, set forth in the appended claims and illustrated 15 in the accompanying drawings, wherein:

Figure 1 is a side elevation of the improved casting machine partly in section.

Fig. 2 is a vertical sectional view through the cap plunger.

Fig. 3 is a fragmentary view showing the cap and plunger depressed.

Fig. 4 is a front elevation partly in section.

Where dental casting machines are used in which the molten metal is subjected to the action of compressed air, it is very necessary that the air be admitted automatically so that one of the hands of the operator shall remain free to attend to other matters. In order to easily and quickly produce this result a machine is provided consisting of the base 5 and upright 6, the latter having the overhanging member 7 with an opening 8 through which plays a plunger 9 having a cap 10 at its lower end and directly above the flask 11 that is supported on a platform 12 of the base 5.

The flask 11 may be of any desired type to contain the mold while the cap 10 may be provided with the necessary packing to 45 make an air tight fit so that the compressed air will not escape, and the upper end of the plunger 9 carries a valve casing 13 with an inlet pipe 14 at one side and an outlet pipe 15 at the other side and the latter is flexible 50 and communicates with the interior of the cap 10. The communication between the inlet and the outlet is interrupted by the valve 16, as will be seen in Fig. 2, carried at the upper end of a rod or stem 17 whose lower 55 end is screwed into the hub 18 of the cap

10. The weight of the cap seats the valve and the compressed air from the pipe 14 is normally shut off. A certain amount of play is allowed the end of the plunger in the hub 18 so that the rod 17 and the valve 60 may move independently.

The plunger is operated by a lever 19 pivoted to a link 20 that is loosely bolted to a lug 20' on the member 7 while a goose neck 21 extends upward and forms a guide for 65 the plunger. The angular extension 22 of the lever 19 is pivoted to the collar 23 that encircles and is secured to the plunger and limits its upward and downward movement.

When the plunger is depressed into the 70 position shown in Fig. 3 the movement of the cap is arrested by the flask but the plunger continues its movement until it rests in the recess of the hub 18 and causes the valve seat 25 to drop away from the valve so that 75 the compressed air passes through the casting 13 and the outlet pipe 15. On reaching the cap the inrushing air is diffused by the inclined nipple 26 to prevent injury to the 80 molten metal and its being blown from the mold.

It is obvious that while the parts shown and described are simple and readily operable they may be modified and otherwise arranged without departing from the essential features above described or from the scope of the appended claims.

What I claim as new is:

1. In a dental casting machine, the combination of a flask, a cap to close the same, a source of compressed air for the cap, a valve controlling the same, a plunger loosely playing on and adapted to depress the cap and carrying the valve, means for operating the plunger, and a stem below the valve 90 and attached to and adapted to be operated by the cap to open the valve when it is seated on the flask.

2. In a dental casting machine, the combination of a flask for a mold, a cap with 100 a nipple to close the same, a compressed air pipe connected to the nipple, a plunger with a head constituting a part of the air pipe, a valve closing the air pipe, a stem to the valve and secured to the cap, means for providing lost motion between the plunger and the cap, and means for depressing the plunger.

3. In a dental casting machine, the combination with a flask for a mold, of a cap 110

- adapted to close the same, a plunger above the cap, means for operating the plunger, a valve casing at the top of the plunger and having an air outlet, an outlet pipe connecting the casing with the interior of the cap, a valve between the inlet and outlet, a valve stem secured to the cap and enveloped by the plunger and means for opening the valve when the cap is seated on the flask.
4. In a dental casting machine, the combination with a flask, of a cap for the same, an upright, a plunger having the cap at its lower end and playing through the upright, a valve casing at the top of the plunger, air supply means passing through the casing to the cap, an interposed valve, a stem for the same passing down the plunger and attached to the cap, means for affording movement
- of the cap on the plunger, and a lever operating the plunger.
5. In a dental casting machine, the combination with a flask, of an upright with an overhang, a plunger playing through the latter, a cap playing on the end of the plunger, a valve casing at the top of the plunger and having an inlet, an outlet pipe for the air and connected with the interior of the cap, a valve interposed between the inlet and outlet, a stem for the valve and suspending the cap, and a lever operating the plunger.

Signed at 354 Livingston street, in the county of Kings and State of New York, this 21st day of November, A. D. 1917.

JOHN E. BURNS.
